Arash Behravesh(57) **CLAIM**

What is claimed is the ornamental design for a wheel for a motor vehicle, as shown and described.

DESCRIPTION

FIG. 1 is a perspective view of a wheel for a motor vehicle, showing my new design;

FIG. 2 is a top view thereof;

FIG. 3 is a back view thereof;

FIG. 4 is a side view thereof;

FIG. 5 is a cross-sectional view thereof, taken along line V-V in FIG. 2;

FIG. 6 is a perspective view of a second embodiment of a wheel for a motor vehicle showing my new design; and,

FIG. 7 is a cross-sectional view of the wheel for a motor vehicle in FIG. 6, taken along line VII-VII in FIG. 6.
